UNITED STATES PATENT OFFICE.

PUTNAM D. SMITH, OF WATERLOO, IOWA.

SPIRIT-LEVEL.

SPECIFICATION forming part of Letters Patent No. 730,487, dated June 9, 1903.

Application filed August 19, 1902. Serial No. 120,187. (No model.)

To all whom it may concern:

Be it known that I, PUTNAM D. SMITH, a citizen of the United States of America, and a resident of Waterloo, Blackhawk county, 5 Iowa, have invented certain new and useful Improvements in Spirit-Levels, of which the following is a specification.

My invention relates to improvements in spirit-levels; and the object of my improvement is to greatly increase the responsiveness of the instrument to slight changes of level by controlling its action through the oscillation of a weight connected to it by compound levers. This object I attain by the mechanism which is illustrated in the accompanying drawings, in which—

Figure 1 is a side elevation of my improved weight-controlled spirit-level as detached from its frame. Fig. 2 is an end elevation 20 of the same with one side brace removed; and Fig. 3 is an under view of the same with the weight, bottom, and side pieces detached.

Similar letters refer to similar parts throughout the several views.

25 The top plate *a* and the bearing-plate *b* are provided with the oblong opening shown, through which the spirit-level tube *o* may be seen. The tube *o* is fastened horizontally within the oblong frame *s*, and the latter is 30 suspended pivotally on bolts passing through hangers depending from the bearing-plate *b*, so as to maintain in equilibrium a horizontal position. One end of the frame *s* is lengthened out into a depending hook-shaped bearing-piece *p*, through which from top to bottom extends an adjusting-screw *q*. From the end of the tube *o* nearest the hook *p* a rod *r* extends horizontally, movable vertically through the vertical slot in said hook *p*. This 35 rod is provided medially with a flattened portion containing a bearing through which works the adjusting-screw *q*. The adjusting-screw extends outwardly through the plate *a*, so as to be accessible from the outside of the 40 level. Levers *n* are suspended from pivot-studs attached to hangers depending from the plate *b*. The lower sides of these levers are connected together by a horizontal plate from which depends a weight-carrying tongue-piece *g*. This tongue-piece passes vertically 45 through an opening in and sustains the cylindrical weight *f*. The tongue-piece *g* also

passes through an opening in the bottom plate *e* and is kept in place by means of a pin *h*, which passes through a slot at its tip. Slidable side pieces *d* engage notches in the hangers *c* and in the bottom piece *e*. The pivot-studs on which the levers *n* are suspended form their fulcrums, and the longer ends of these levers extend horizontally toward the adjusting-screw and are parallel with the long sides of the frame *s*. A link *l* is pivotally suspended from a hanger attached to the plate *b* and is pivoted into and forms a fulcrum-support for one end of the lever *i*. The other 60 end of the lever *i* is pivotally connected to one of the side bars of the frame *s* by means of a link *m*. The tip of the long arm of the lever *n* on the same side is pivotally connected with the lever *i* at a point inside of 65 and close to the connection with the link *l* by a link *k*.

The function of the suspended weight *f* in controlling the action of the spirit-level *o* is thus described: When the cylinder *f* has been 70 very exactly adjusted so that the tongue-piece *g* supports it on a line extending through its center of gravity, a very slight displacement of the level-box from the horizontal causes said weight to exert a multiplying effect upon the movement of the spirit-level tube. This effect is caused by means of the action of the intermediate compound levers. The swinging of the weight *f*, which is but slightly resisted by the slidable pieces *d*, 75 raises or lowers the long arms of the levers *n*, which by means of the link *k* raises or lowers the lever *i*. The movement communicated to the lever *i* is communicated to and raises or lowers that end of the spirit-level 80 tube-frame *s* farthest from the adjusting-screw *q* by means of the link *m*. The delicacy in responsiveness to slight changes of level on the part of the tube *o* is thus greatly magnified. Exact adjustments of the frame *s* 85 may be effected by means of the adjusting-screw *q*, by whose action the rod *r* may be raised or lowered.

It is obvious that the method of controlling and magnifying the effect of slight changes 90 of level on the spirit-level tube by means of a weight and intermediate levers is the essence of my invention, and such changes in the parts and their relative positions as may

be necessary to adopt in varying forms of levels will still be comprehended in the scope of my invention.

Having described my invention, what I claim as new, and desire to secure by Letters Patent, is—

1. A weight-controlled spirit-level, composed of a tube mounted within a pivotally-balanced frame, a pivotally-balanced frame, a compound lever connected to said frame and to a suspended tongue-piece, a suspended tongue-piece and a weight supported by said tongue-piece, substantially as shown and described.
- 15 2. A weight-controlled spirit-level, composed of a tube mounted within a pivotally-balanced frame, a pivotally-balanced frame, a compound lever suspended intermediately between said frame and a weight, a weight and means for supporting it, all having suitable connections and supports, substantially as shown and described.
- 25 3. A weight-controlled spirit-level, composed of a tube mounted within a pivotally-balanced frame, a pivotally-balanced frame, means for adjusting said frame, a compound lever suspended intermediately between said frame and a weight, a weight and means for supporting it, all having suitable connections and supports, substantially as shown and described.
- 30 4. A weight-controlled spirit-level, composed of a casing *a*, a spirit-tube *o* mounted in a frame *s* pivotally supported from said

casing *a*, a pivotally-balanced frame *s*, a compound lever consisting of the parts *m*, *i* and *k* fulcrumed in a link *l* suspended from said casing *a* and connected intermediately between said frame *s* and a pivoted hanger *n*, a hanger *n* pivotally supported by said casing *a*, having a tongue-piece *g*, pin *h* and detachable plate *e* and weight *f*, and slidible side pieces *d*, substantially as shown and described.

5. A weight-controlled spirit-level, composed of a casing *a*, a spirit-tube *o* mounted in a frame *s* pivotally supported from said casing *a*, a pivotally-balanced frame *s*, a depending slotted bearing-piece *p* extending from said frame *s*, a flattened bearing-rod *r* attached to said spirit-tube *o* and an adjusting-screw *q* adapted to work within said rod *r* and piece *p*, a compound lever consisting of the parts *m*, *i* and *k* fulcrumed in a link *l* suspended from said casing *a* and connected intermediately between said frame *s* and a pivoted hanger *n*, a hanger *n* pivotally supported by said casing *a*, having a tongue-piece *g*, pin *h* and detachable plate *e* and weight *f*, and slidible side pieces *d*, substantially as shown and described.

Signed at Waterloo, Iowa, this 12th day of August, 1902.

PUTNAM D. SMITH.
